(57) **CLAIM**

The ornamental design for an AR series firearm takedown pin, as shown and described.

DESCRIPTION

FIG. 1 is an exploded perspective view of the both embodiments of an AR series firearm takedown pin, showing my new design;

FIG. 2 is an exploded view of the first embodiment of an AR series firearm takedown pin, which is the front takedown pin;

FIG. 3 is a perspective view thereof;

FIG. 4 is a front view thereof;

FIG. 5 is a rear view thereof;

FIG. 6 is a right side view thereof;

FIG. 7 is a left side view thereof;

FIG. 8 is a top view thereof;

FIG. 9 is a bottom view thereof;

FIG. 10 is an exploded view of the second embodiment of an AR series firearm takedown pin, which is the rear takedown pin;

FIG. 11 is a perspective view thereof;

FIG. 12 is a front view thereof;

FIG. 13 is a rear view thereof;

FIG. 14 is a right side view thereof;

FIG. 15 is a left side view thereof;

FIG. 16 is a top view thereof; and,

FIG. 17 is a bottom view thereof.

The evenly broken lines in the drawings depict unclaimed portions of the AR series firearm takedown pin; additionally, the evenly broken lines in FIG. 1 depict unclaimed environmental subject matter; the Dash-dot broken lines in the drawings disclose projection lines; the broken lines form no part of the claimed design.

1 Claim, 5 Drawing Sheets
